UNITED STATES PATENT OFFICE.

KENNETH S. BAXTER, OF MICHIGAN CITY, INDIANA, ASSIGNOR TO SHEET STEEL PRODUCTS COMPANY, OF MICHIGAN CITY, INDIANA, A CORPORATION OF INDIANA.

CAB-DOOR.

1,390,483.

Specification of Letters Patent. Patented Sept. 13, 1921.

Application filed October 15, 1920. Serial No. 417,109.

To all whom it may concern:

Be it known that I, KENNETH S. BAXTER, a citizen of the United States, and a resident of Michigan City, county of La Porte, and 5 State of Indiana, have invented certain new and useful Improvements in Cab-Doors, of which the following is a specification and which are illustrated in the accompanying drawings, forming a part thereof.

10 The invention relates to cab doors and has as an object the provision of such a door without a frame that shall be durable and of pleasing appearance. A further object is the provision of a combination of joints for securing the parts of such a door to each other.

15 An illustrative embodiment of the invention is shown in the accompanying drawings, in which;

Figure 1 is an elevation of the door from 20 the side which is designed to be placed toward the interior of the vehicle;

Fig. 2 is an edge view from the right of Fig. 1;

Figs. 3 and 4 are sections on lines 3—3 and 25 4—4 respectively of Fig. 1, the sections drawn on an enlarged scale;

Fig. 5 is a detail perspective of the upper joint of the door, an end of the view being in section.

30 The complete door is shown as comprising two sheet metal panels 10 and 11. In the form of the invention chosen for illustration the inside panel 10 has its lower margin 13 and its side margins 14 and 15 bent 35 at right angles to the body of the panel, as at 16, and again at right angles, as at 17, into a plane parallel with the body of the panel. The corresponding margins of the outer panel 11 are placed in contact with 40 the portions 17 of the inside panel and are then folded thereabout, as at 18. This method of securing the panels together provides a flange 19 upon three sides of the door which comprises three thicknesses of 45 metal and is adapted to overlap the sides of the vehicle body when in use.

The upper margin of the outer panel 11 is bent at right angles to provide an edge of the door 19^a equal in thickness to that 50 formed by the portion 16 of the panel 10. The said upper margin is then bent downwardly, then outwardly and upwardly to provide the reverse bend 20. A corresponding, but opposed reverse bend 21 is formed 55 on the upper margin of the inside panel 10

and a locking strip 22 is then slipped over the portions 20, 21. When the strip is in place it is desirable to secure the ends of the joint as by the action of an oxy-acetylene flame.

60 The strip 22 not only adds stiffness to the upper edge of the door but also provides a pleasing finish with a rounded corner. If desired an opening 23 may be formed in the inner panel to make possible the use of 65 the interior of the door as a pocket. When so formed the panel is preferably provided with a stiffening corrugation, as at 24.

I claim as my invention:

1. A frameless sheet metal half-door comprising, in combination, two sheet metal panels constituting respectively the inner and outer faces of the door, flanges on the two side edges and on the bottom edge of the inner panel parallel with but offset from the 75 plane of the body of the inner panel and lying against the inner face of the outer panel, the corresponding margins of the outer panel being folded about said flanges and forming therewith an inwardly facing 80 stop engaging shoulder comprising three thicknesses of metal extending about the said three sides of the door adjacent the plane of the outer face of the door, and a stiffening rib extending across the top of the door upon 85 the inside face of the same produced by folding the upper marginal portion of the inner panel outwardly and downwardly and folding the upper marginal portion of the outer panel inwardly to the plane of the 90 inner panel thence downwardly to meet the folded upper edge of the inner panel and finally outwardly and upwardly substantially to the plane of the upper edge of the door, the said outwardly and downwardly folded portion of the inner panel and the said outwardly and upwardly folded portion of the outer panel respectively providing downwardly and upwardly facing 95 parallel channels extending throughout the 100 width of the door, and a locking strip covering the said meeting folded edges of the outer and inner panels throughout the width of the door, the longitudinal edges of the locking strip being inwardly folded upon 105 the body of the strip and entering the said downwardly and upwardly facing channels respectively.

2. A sheet metal half-door comprising, in combination, two sheet metal panels consti- 110

2
tuting respectively the inner and outer faces
of the door, means connecting the panels
along their side and bottom edges, and a
stiffening rib extending along the upper edge
5 of the door upon one of its faces produced
by folding the upper marginal portion of
the adjacent panel outwardly and down-
wardly and folding the upper marginal por-
tion of the other panel inwardly to the plane
10 of the first separately mentioned panel
thence downwardly to meet the folded upper
edge of the said first panel and finally out-
wardly and upwardly substantially to the
plane of the upper edge of the door, the

said outwardly and downwardly folded por- 15
tion of the said first panel and the said out-
wardly and upwardly folded portion of the
other panel respectively providing down-
wardly and upwardly facing parallel chan-
nels extending throughout the width of the 20
door and a locking strip covering the said
meeting folded edges of the two panels
throughout the width of the door, the longi-
tudinal edges of the locking strip being in- 25
wardly folded upon the body of the strip
and entering the said downwardly and up-
wardly facing channels respectively.

KENNETH S. BAXTER.
